UNITED STATES PATENT OFFICE.

HERBERT L. ANDREWS, OF CHICAGO, ILLINOIS.

DESIGN FOR FABRIC.

SPECIFICATION forming part of Design No. 30,166, dated February 7, 1899.

Application filed January 3, 1899. Serial No. 701,051. Term of patent 14 years.

To all whom it may concern:

Be it known that I, HERBERT L. ANDREWS, a citizen of the United States, residing at Chicago, in the county of Cook and State of Illinois, have invented and produced a new and novel Design for a Fabric, of which the following is a specification, reference being had to the accompanying drawings, in which—

Figure 1 is an upper face view or plan thereof; Fig. 2, an under face view or plan; Fig. 3, a vertical sectional view of Figs. 1 and 2 on lines 3 3.

A reference-letter applied to designate a given part is used to indicate such part throughout the several figures.

My novel design of fabric comprises a substantially horizontal webbing composed of parallel strands slightly wavy in appearance and presenting a smooth upper surface (marked A on the drawings) and having depending ribs on the under surface extending at right angles to the parallel strands of the horizontal webbing, such ribs being marked B on the drawings.

The ribs B B are particularly observable when the fabric is stretched taut.

The fabric is particularly used by me for the

seats and the backs of opera-chairs, for the seats of music-stools, and the like. In such use it is stretched taut and secured at the several edges thereof.

The leading features of this design are that when viewed from the top the fabric consists in the apparently smooth and slightly-wavy upper face comprising diagonally-extending and substantially parallel strands, (lettered a a in the drawings,) and when viewed from the under side or in sectional view the fabric consists of a thin substantially horizontal webbing, with heavy ribs or ribbing depending therefrom, the strands constituting the substantially horizontal webbing extending at substantially right angles to the heavy ribbing depending from the under side thereof.

Having described my invention, what I claim as new, and desire to secure by Letters Patent, is—

The design for a fabric, as herein shown and described.

HERBERT L. ANDREWS.
